(57) **CLAIM**

The ornamental design for a removable track unit for a robotic vehicle, as shown and described.

DESCRIPTION

FIG. 1 is a front left side perspective view of the removable track unit for the robotic vehicle showing our new design; FIG. 2 is a rear left side perspective view thereof; FIG. 3 is a front view thereof;

FIG. 4 is a left side view thereof;

FIG. 5 is a rear side view thereof; and,

FIG. 6 is a top side view thereof.

The broken lines in the figures illustrate portions of the removable track unit for the robotic vehicle that form no part of the claimed design.
